UNITED STATES PATENT OFFICE.

WILLIAM L. HUDSON, OF LYNCHBURG, VIRGINIA, ASSIGNOR TO ALLEN MORRISON SIGN CO., INC., OF LYNCHBURG, VIRGINIA.

WIND-MOTOR SIGN.

Application filed January 10, 1922. Serial No. 528,229.

To all whom it may concern:

Be it known that I, WILLIAM L. HUDSON, a citizen of the United States, residing at Lynchburg, in the county of Campbell and State of Virginia, have invented certain new and useful Improvements in Wind-Motor Signs, of which the following is a specification.

This invention relates to new and useful improvements in advertising devices, and more particularly to improvements upon a device of the character disclosed in my co-pending application for wind motor signs, S. N. 472,987, filed May 27th, 1921.

The important object of the present invention resides in the provision of a sign having oppositely disposed advertising devices or means for attracting attention to the sign associated therewith and which can be transposed or interchanged so that their positions with respect to the sign will be reversed, thereby eliminating certain precautions which would have to be taken in lettering the sign and advertising devices if the latter were not interchangeable.

Auxiliary to this object is to provide an inexpensive and yet durable construction for the various parts for the accomplishment of the purpose above set forth in a commercial manner.

Other objects and advantages of the invention will become apparent during the course of the following description.

In the accompanying drawings forming a part of the description and wherein like numerals are employed to designate like parts throughout the several views.

Figure 1 is a side elevation of the invention.

Figure 2 is a top plan of the same, and

Figure 3 is an end elevation of the wind wheel frame.

In the drawings wherein for the purpose of illustration is shown the preferred embodiment of the invention, the numeral 5 designates a post or any desired support from which rises a rod 6 for rotatably mounting a sign 7 as disclosed in the above mentioned co-pending application. The sign 50 in the present instance consists of a pair of spaced parallel, oppositely disposed panels 8 secured face to face, whereby the advertising matter or the outer faces of the panels are visible from opposite sides of the sign.

An upright bar 9 is fastened by any suitable means between the panels 8 at each end of the sign, it being noted that the ends of the bars project above and below the sign or panels and are apertured for the reception of bolts 10.

The advertising devices which provide additional advertising space and means for attracting attention to the panels consists of a wind wheel 11 and a vane or elongated board 12. This board is fastened to a carrier 13 in the form of a bar which is the same length as the bars 9 and has its ends provided with apertures to align with those of both bars 9 so that it can be attached to either one of these bars and be arranged in the same plane with the panels.

The wind wheel may be of any desired construction so as to be rotated by the wind and is demountably connected in a frame 14. This frame consists of a pair of bars 15 retained in spaced parallel relation by rods 16 in the same manner as disclosed in my co-pending application. The bars 15 are each equipped with a bearing for the axle of the wind wheel and the ends of the inner bar of the frame are provided with apertures adapted to align with those in the bars 9 forming a part of the sign. It will therefore be appreciated that the wind wheel frame can also be detachably connected to either end of the sign or panels; therefore the vane and wind wheel frame are interchangeable with respect to the sign.

To illustrate the advantages of providing for the interchange of the wind wheel frame and vane, it is desired to point out that oftentimes the signs are purchased by two parties having different advertisements to display and who desire an even apportionment of advertising space. Consequently, the parties may desire an advertisement placed upon both sides of the advertising device, each having one side of the central sign and the opposite side of the vane, or each may desire one side of the central sign and the corresponding side of the vane. Were it not for the fact that the frame 14 and vane were interchangeable so that either one could be attached to either end of the sign proper, it will be seen that precaution would have to be exercised in lettering the sign and vane to anticipate the desires of the joint purchasers. Since the advertising devices

are interchangeable, the advertisements of the joint purchasers may be painted upon either side of the vane, and the purchasers upon receiving the wind motor sign may assemble the same in the manner they desire or change the arrangement from time to time. As the vane and wind wheel frame are detachable from the sign proper and the latter can be removed from the rod 6, it will be seen that the device can be crated compactly and shipped in the minimum amount of space.

The operation of the advertising device is the same as the device disclosed in my above mentioned co-pending application with regards to the operation of the wind upon the device, it being appreciated that the sign proper and the vane will act in the capacity of a weather vane to shift the device so that the wind wheel 11 will be rotated whenever there is any wind. The blades of the wind wheel are painted with various combinations of bright colors so that rotation of the wheel will attract attention to the advertising matter situated on the panels 8 and vane 12.

The foregoing description and the accompanying drawings have reference to the preferred or approved embodiments of my invention. It is to be understood however, that such changes may be made in the construction and arrangement of parts, materials, dimensions, etc., as may prove expedient and fall within the scope of the appended claims.

Having thus illustrated and described my invention, what I now claim as new and desire to secure by Letters Patent is:

1. A device of the class described comprising a plurality of signs having advertising data on opposite sides thereof, one of said signs being demountably attached to the other signs, and adapted to be attached to either end of said other sign whereby the advertising data on opposite sides of the signs can be arranged in the desired relationship.

2. A device of the class described comprising a sign board, a wind wheel frame detachably connected to one end thereof, a vane detachably connected to the other end of the board, and said frame and vane being interchangeable.

3. A device of the class described comprising a rotatable sign board having apertured parts at each end thereof extended beyond the top and bottom of the board, a wind wheel frame detachably connected to the apertured parts at one end of the board, and a vane carrier connected to the apertured parts at the opposite end of the board, said frame and carrier being interchangeable.

4. A device of the class described comprising a rotatable sign consisting of a pair of panels, an upright bar fastened to each end of the sign between the panels thereof,

the opposite ends to the bars being extended above and below the sign and apertured, a wind wheel frame and a vane carrier having apertures to align with the apertures in the ends of the bars, bolts for detachably connecting the frame and the carrier to the upright bars, and said frame and carrier being interchangeable with relation to the sign.

5. An advertising sign comprising a body portion adapted to contain advertising matter, an advertising device having advertising matter on opposite sides thereof, and said advertising device being attachable to either end of the sign whereby the advertising matter of each side of the device can be arranged in proper relationship to the advertising matter on the body portion.

6. An advertising device comprising a rotatable sign board a wind wheel frame detachably mounted on one end thereof, an advertising container detachably connected to the other end of the sign board and having advertising matter on opposite sides thereof, and said frame and container being interchangeable with respect to each other and in relation to the sign board.

7. A device of the class described comprising a sign board having advertising data on opposite sides thereof, an attention attracting device detachably mounted on one end of the sign, and a sign having advertising data on opposite sides thereof and detachably mounted on the other end of the sign board, said sign and attention attracting device being attachable to either end of said sign board whereby the advertising data on either side of the sign can be arranged in the desired relationship to the advertising data on either side of the sign board.

8. A device of the class described comprising a sign, a rotatable member detachably connected thereto, and a vane detachably mounted on the sign, said rotatable member and vane being interchangeable.

9. A device of the class described comprising a revolving sign board, a rotatable member detachably connected to one end thereof, a vane containing advertising data on opposite sides thereof and detachably mounted on the other end of said sign board said sign board having advertising data on opposite sides thereof, and said rotatable member and vane being interchangeable whereby the advertising data on the vane can be arranged in the desired relationship to the advertising data on the sign board.

10. A device of the class described comprising a sign having opposite ends provided with openings, a frame for an attention attracting device and a vane having openings to align with the openings in either end of the sign whereby the frame and the vane may be attached to either end of the sign so that advertising data on the

vane can be arranged in the proper relationship to the advertising data disposed on opposite sides of the sign.

11. A device of the class described comprising a sign, an attention attracting device demountably attached to one end of the sign, and a vane detachably connected to the other end of the sign, said vane and attention attracting device being interchangeable whereby advertising data on the vane can be arranged in the proper relationship to the advertising data on the sign.

12. A device of the class described comprising a sign board having advertising data on opposite sides thereof, an attention at-

tracting device detachably mounted on one end of the sign, and a sign having advertising data on opposite sides thereof detachably connected to the other end of the sign board, said sign and attention attracting devices being interchangeable whereby the advertising data on the sign can be arranged in the desired relationship to the advertising data on the sign board.

In testimony whereof I affix my signature in presence of two witnesses.

WILLIAM L. HUDSON.
